UNITED STATES PATENT OFFICE.

HILAIRE DE CHARDONNET, OF PARIS, FRANCE.

MACHINE FOR SPINNING ARTIFICIAL SILK.

1,209,133.

Specification of Letters Patent. Patented Dec. 19, 1916.

Application filed July 16, 1915. Serial No. 40,271.

To all whom it may concern:

Be it known that I, HILAIRE DE CHARDONNET, a citizen of France, residing at 22 Place Malesherbes, Paris, in the Republic of France, have invented new and useful Improvements in Machines for Spinning Artificial Silk, of which the following is a specification.

This invention relates to improvements in machines for spinning artificial silk from collodion of a uniform composition throughout.

The invention consists of a novel combination and arrangement of parts characterized by the fact that the group of threads to be wound together on each bobbin and subsequently twisted are assembled on a separate feed table which is supplied with collodion by means of a two-barrel feed pump, the movements of the pump plungers coacting so as to insure a constant uniform flow of collodion to the feed table. The movement of each pump plunger when forcing the collodion through the spinning nozzles is slower than the indrawing movement of the same when filling the pump barrel so that one plunger continues to feed the collodion while the distribution-cock of the other barrel is turning at the end of every stroke, whereby all interruption to the outflow of collodion at the dead point is avoided while slight variations in the collodion flow are compensated automatically by a spring pressure regulator or accumulator on each feed table.

The pump barrels are divided into two sets or series, the plungers of each series being actuated alternately to force the collodion into the feed tables.

The collodion entering the pump barrels under pressure tends constantly to raise the pump plungers, this tendency being counteracted to the extent of the minimum pressure used in spinning by counterweights applied under the plungers so that the power necessary to force each plunger and its connections downward against the resistance of the collodion corresponds to the difference between the maximum and minimum pressures reached in spinning.

A constant count ("titerage") of thread is obtained by maintaining an invariable ratio between the bobbin surface speed and the flow of collodion supplied to each group of capillary glass spinning nozzles, the threads from which are wound together

upon a given bobbin, and subsequently twisted and spun.

The description which follows, together with the accompanying drawings, explains clearly the arrangement of the improved machine which achieves this result.

Figure 1 is a transverse vertical section of the whole machine, the section being made on the plane of the line A A, Fig. 3. Fig. 2 is a transverse section on the line B B, Fig. 3. Fig. 3 is a sectional plan of the machine on the plane of the line D D, Fig. 1. Fig. 4 is a side sectional elevation of the machine taken on the line C C, Fig. 3. Fig. 5 is a plan of the rollers, bobbins, guide arms, and traverse motion, showing the driving drum on one side only of the frame. Fig. 6 shows separated, on a larger scale, a tube-bobbin and its spindle. Fig. 7 is a side elevation of the grooved cam pulley shown in dotted lines in Fig. 4. Fig. 8 is a view of the rim of the cam pulley, Fig. 7. Fig. 9 shows in vertical section a twisting spindle with a tubular bobbin filled with thread. Fig. 10 shows in elevation, on a larger scale, a feed table with its regulator, the spring being open. Fig. 11 is a plan of the feed table. Fig. 12 is a vertical section of the feed table and its regulator, the spring being closed. Fig. 13 is a plan of the top of the regulator showing the thread-guides. Fig. 14 shows, in front elevation, the pump-barrel with its three-way distribution cock, the piston being at the top of its stroke. Fig. 15 is a vertical section of the structure shown in Fig. 14. Fig. 16 is a horizontal section of the three-way distribution cock. Fig. 17 is a plan of the three-way distribution cock and its actuating means. Fig. 18 is an elevation of Fig. 17.

The improved machine forming the subject of the invention is in the same general form as other known machines for spinning artificial silk from collodion or the like and is inclosed in a casing as sometimes customary. The casing is in this instance closed in front of the threads, either by movable panes of glass or by curtains of transparent gauze, which are set aside to get at the threads. These curtains or glasses, not shown, are suspended upon the framing at a. The machine is closed above by panes of glass b, which are opened when required for replacing the full bobbins c' by empty bobbins c. On the inside walls of the machine are fixed hooks d, as shown on the right

hand side of Fig. 1, upon which are placed the full bobbins c' , shown on the opposite side of the same figure, to allow them to dry partially.

- 5 To accelerate the descent of the air, charged with heavy vapors, toward the bottom of the machine, whence it is drawn off by a fan or equivalent toward the regenerating apparatus, an uncongealable 10 cooling liquid can be caused to circulate in tubes e , either plain or ribbed.

The capillary spinning nozzles 2 (see Fig. 10) feeding a given bobbin are assembled upon a circular feed table f mounted upon a hollow vertical spindle f' , shown in Fig. 12, rotating in a water-tight packing, and through which the collodion is injected into the feed table f through a filter f'' . This feed table f carries as many spinning nozzles 2 as the threads that are to be assembled upon a given bobbin. In Fig. 11 it has been assumed that there were ten nozzles to one bobbin; but only two are shown in position on Figs. 10 and 11. In this way, 25 each nozzle 2 can be brought forward when required. The fixed lower part of the feed table f containing the water-tight packing is bolted to a girder-beam of the framing and carries a three-way cock 3 enabling the 30 collodion to be run off if necessary.

In the middle of the feed table f is arranged vertically a pressure regulator consisting of a coiled spring h or its equivalent. This pressure regulator as shown is formed of a tubular column i , slotted at the sides to receive the ends of a guide bar or crosspiece connecting the packed plunger rod or piston k to a tube j , which is fitted to slide vertically upon the column i ; the tube j is 40 flanged at the bottom to form a shoulder which acts as an abutment for the spring h .

At the top of column i is screwed a ring or collar m which acts as the upper abutment for the spring h , and upon which is placed 45 a ring n which carries the thread-guides o . The ring n must be removed temporarily to allow a cap or casing l to be placed over the spinning nozzles.

The flow of collodion being constant, if 50 the outlet through the spinning nozzles 2 offers more or less resistance on account of accumulation of dirt or from any other cause, the spring h furnishes automatically the requisite pressure for the outlet of the 55 collodion which is thus effected in a constant volume and under a variable pressure.

When the spinning is interrupted, the spinning nozzles 2 must be covered with the annular cap or casing l , which prevents 60 hardening of the collodion and facilitates re-starting the machine.

Each spinning head or feed table f receives the collodion from a pump formed of two separate barrels p and p' . One of these barrels is seen on a larger scale in Figs. 14

and 15. The motion of the plunger q of each barrel is regulated so as to run more slowly when forcing the collodion into the spinning nozzles 2 than when the suction is taking place. The object of this arrangement is to prolong the action of the plunger q of one of the pump-barrels during the action of the valves or taps of the other pump-barrel, and taking into account the lost motion. It results from this that the 75 flow of the collodion is constant as no dead point can exist. It is only to guard against any possible irregularities of working that the above described auxiliary spring regulator h has been adopted. The differential plunger q of each of these single-action pumps p p' traverses it from one end to the other in glands or stuffing boxes. The collodion is forced into the spinning nozzles 2 when the plunger q descends, according to 85 the difference of diameters at the top and at the bottom. The collodion arrives from the supply pipe g under pressure, so that the plungers q are always raised by the collodion, but this pressure is compensated in 90 the following manner: All the pump-barrels of the machine are divided into two sets p and p' which are held parallel by means of connecting collars in grooved framings r r' forming racks, which are bolted on to 95 small cast-iron columns s which support all the lower part of the machine. The distribution cocks N are supported in a stationary bar W .

Under each of the racks r r' is a beam t 100 movable vertically along slides u . These beams run the length of the machine; each of them is formed of a flat plate placed vertically, and provided with horizontal flanges; the upper flange is provided with 105 holes through which pass the rods q of the pump plungers. A washer q' and a nut q'' , see Figs. 14 and 15, screwed to the bottom of the rod, draw down the plunger q when the beam t descends. Under the beams t 110 are suspended counterweights v which are regulated so as to balance the minimum pressure of the collodion under the plungers q . If left to the sole action of the collodion, the system formed by the plungers q , the beams t 115 and the counterweights v , would be constantly brought back to the top of its stroke. The power necessary to move this "system" will be therefore always directed from above to below, but it will never exceed the difference of the maximum and minimum pressures used in spinning and acting under the plungers q ; this effect will thus be reduced to a minimum.

To cause the beams t to travel with uniform movements upward and downward at the respective speeds required, each beam is provided, near both ends, with rollers z which move in the grooved paths z z' (see Figs. 2 and 7) in the sides of a cam pulley 120

y whose grooved paths have different inclines proportioned to the vertical speed of translation in each direction. There is a cam pulley *y* at each end and both pulleys 5 are rotated at a constant speed as herein-after described.

At each end of the stroke one of the plungers *q* continues to thrust the collodion while the other is at dead point and while 10 the distribution-cock *N* of this latter takes up the new position. On Fig. 7, the path *z* which corresponds to the plungers of the pumps *p*, is shown in full lines, while the path *z'* corresponding to the plungers of 15 the pumps *p'* and which is situated on the opposite side of the cam pulley *y* is indicated in dotted lines.

To effect the rotation of all the distribution-cocks *N* of a given set, the rim of each 20 cam pulley *y* is provided, as shown in Fig. 8, with say three or it might be two circular grooves 4 connected with each other by oblique grooves 5, which correspond each one to the angle of position occupied by the cam pulley *y* at the moment in which the cocks have to move.

Studs or rollers *I* (see Fig. 2) running in these circular grooves 4 and passing from one to the other by the oblique grooves 5 at 25 the right moment, transmit their lateral movement by a set of connecting rods which are clearly seen in the plan Fig. 3, and by means of a vertical shaft carrying two disks *E* the lower disk *E* having two bars *F* pivotally connected to it and running along the machine above the distribution-cocks *N*. The fixed center *T'* of the connecting rod system is mounted upon a bearer or cradle connecting the two racks *r r'* above the cam 40 pulley *y*. The bars *F* (see Fig. 17) carry studs corresponding to holes in the double-ended spanners *G* of the distribution-cocks *N* and thus cause them all to partially rotate simultaneously.

45 The shaft *H* of each cam pulley *y* carries a worm wheel *K* gearing with a worm *L*, keyed upon a driving shaft *M* extending from one end to the other of the machine and thus causing both cam pulleys *y* to be 50 rotated at the same speed. The shaft *M* is connected by gearing or belt to the axle of the drum by which the bobbins are driven by frictional contact to insure that the two speeds (of drawing and of flow of collodion) 55 shall be in a constant ratio corresponding to the required count of the thread or yarn.

Each distribution-cock *N* has three outlets and makes quarter of a revolution at each end of the stroke, so that these cocks place 60 successively their respective pump-barrels in communication with the feed pipe *g* and the feed table *f*.

In place of the bobbins used usually in spinning, there are used here tube-bobbins 65 of aluminium or brass or other suitable ma-

terial placed, during spinning, upon spindles which rotate in guide arms of the spinning machine. A tube-bobbin *P* and its spindle *Q* are shown separated in Fig. 6. Projecting flanges, one of which is carried by the spindle and the other by the tube, serve for spacing the surface of the tube from that of the cylinder during the first turns of thread. Once the tube-bobbins are filled with thread, they are put to dry partially in the machine upon hooks *d* (Fig. 1), then they are taken to a twisting machine.

The spindles of the twisting machine are specially constructed for the tube-bobbin. They have an enlarged part *R* upon which is placed the full tube-bobbin *c*; a thin brass or aluminium cover *S* turns with the spindle and safeguards the thread against the friction of the air and the excess of tension which results from it. The guiding thread-wire *o'* is placed immediately over the axis of rotation. This cover has near the bottom holes *T* forming apertures to run off the alcoholic drying liquid into a gutter *X*, whence it is conducted to the distillation apparatus in order to recover the remaining alcohol.

The arrangement of draw-off holes is for the purpose of retaining a thin film of liquid against the inside wall of the cover; this liquid film, of a variable thickness, fulfills here the duty of the compensating rings in certain centrifugal drying machines, and which consists in bringing back automatically the center of gravity of the system in coincidence with the axis of rotation.

What I claim as my invention and desire to secure by Letters Patent of the United States is:—

1. In a machine for spinning artificial silk, in combination, spinning nozzles, a rotary feed table therefor, means for feeding collodion, and a pressure regulator comprising a cylinder in communication with the feed table, a plunger in said cylinder, and a spring acting upon said plunger thus exerting pressure upon the collodion.

2. In a machine for spinning artificial silk, a feed table and nozzles, and collodion feeding means in combination with the feed tables comprising a duplex single acting plunger pump, and means for causing the return strokes of the pump plungers to be more rapid than the forward strokes, whereby a continuous delivery is effected.

3. In a machine for spinning artificial silk, a feed table and nozzles, and collodion feeding means in combination with the feed tables comprising a duplex single acting plunger pump, rotary cams to actuate the plungers of said pump, the contours of said cams being such that the return stroke is more rapid than the forward stroke, whereby the flow of the collodion is uninterrupted.

4. In a machine for spinning artificial

silk, a feed table and nozzles, and collodion feeding means in combination with the feed tables comprising a duplex single acting plunger pump adapted to receive collodion under pressure, means to operate said pump, and counterweights attached to the plungers of said pump whereby to exert upon the collodion in the cylinders when the delivery cock is opened a pressure equal to the minimum pressure used in spinning.

5. In machines for spinning artificial silk, bobbins, a power shaft to rotate said bobbins, a series of duplex single acting collodion feed pumps, and means for operating the plungers of said pumps in unison with each other and with the speed of rotation of the said bobbins, comprising beams, interconnecting the right hand plungers and left hand plungers respectively, cams to impart motion to said beams in a direction parallel to the axes of the pump cylinders, and means to rotate the said cams from the said shaft driving the bobbins.
6. In a machine for spinning artificial silk, in combination, feed tables and nozzles, a series of duplex single acting feed pumps,

a double series of three-way distribution cocks, spanners thereon, bars connecting said spanners, and means to operate said bars to effect suction and discharge connections to the pump cylinders.

7. In a machine for spinning artificial silk, in combination, feed tables and nozzles, a series of duplex single acting feed pumps, a double series of three-way distribution cocks, spanners thereon, bars connecting said spanners, a pulley having circumferential cam grooves, and means connecting said bars with said pulley including a stud adapted to engage said grooves, whereby the operation of the cocks is effected.

8. In machines for spinning silk, a tube bobbin flanged at one end, and a spindle adapted to carry said tube bobbin flanged at the opposite end.

In testimony whereof I have signed my name to this specification in the presence of two subscribing witnesses.

HILAIRE DE CHARDONNET.
